PLASTIC SQUEEZE BOTTLE OR SIMILAR ARTICLE

Saburo Ishihara, No. 9, 2-chome, Katayama-cho,
Nagata-ku, Kobe, Japan

Filed Dec. 6, 1961, Ser. No. 67,825

Term of patent 14 years

(Cl. D58—7)

Fig. 5

FIGURE 1 is a front elevational view of a plastic squeeze bottle, showing my new design;

FIGURE 2 is a top plan view;

FIGURE 3 is a bottom plan view;

FIGURE 4 is an elevational view looking from the right of FIG. 1;

FIGURE 5 is a rear elevational view; and

FIGURE 6 is a cross-sectional view taken on line VI-VI of FIG. 2.

I claim:

The ornamental design for a plastic squeeze bottle, substantially as shown.
